US0D1101125S

(12) **United States Design Patent** (10) **Patent No.:** **US D1,101,125 S**
(45) **Date of Patent:** **** Nov. 4, 2025**

(54) **INNER VELOCITY STACK FILTER**

(71) Applicant: **Dennis Duffy Mahoney**, Sandpoint, ID
(US)

(72) Inventor: **Dennis Duffy Mahoney**, Sandpoint, ID
(US)

(**) Term: **15 Years**

(21) Appl. No.: **29/950,004**

(22) Filed: **Jun. 28, 2024**

(51) LOC (15) Cl. **15-01**

(52) U.S. Cl.

USPC **D15/5**; D15/6; D12/400; D23/365

CLAIM

The ornamental design for the inner velocity stack filter as shown and described.

DESCRIPTION

FIG. 1 is a perspective view of the inner velocity stack filter;

FIG. 2 is an exploded view thereof;

FIG. 3 is a top view thereof; and,

FIG. 4 is a bottom view thereof.

1 Claim, 4 Drawing Sheets
